UNITED STATES PATENT OFFICE

2,464,160

WATERTIGHT CABINET JOINT

Jacques Stanitz, Warren, Ohio, assignor to Mullins Manufacturing Corporation, Salem, Ohio, a corporation of New York

Application February 1, 1945, Serial No. 575,645

2 Claims. (Cl. 4—187)

1

The invention relates to the construction of a joint between a kitchen sink and an adjacent cabinet top, or between two adjacent cabinet tops; and more particularly to a sealed, rigid, locked, water-tight, crack-proof joint construction.

Present day kitchens are equipped, in addition to a sink and a cabinet beneath the sink, with work tables, counters or platforms extending from one or both sides of the sink, usually formed as the top of an adjacent base cabinet, to provide a continuous working surface adjacent the sink. Frequently, it is desired to add one or more base cabinets after an initial sink installation or an initial sink and cabinet installation has been made.

Considerable difficulty has been experienced in forming a satisfactory joint between adjacent sink and cabinet units. Many kinds of gaskets, fillers, trim members and cementing have been used, but invariably the joints formed thereby crack open, or the members thereof pull away from each other. Thus, water may find its way into the joint between end wall panels of adjoining metal cabinets, causing an unsanitary condition, failure of paint, and rusting through of the steel. Capillary attraction of water in the space between two metal sheets does not permit the water to run out or to dry up and acts as an accelerated, localized, water emersion test.

Prior art constructions have provided filler, finishing members, cemented between a sink and an adjacent cabinet top; but the joint formed thereby is not rigid nor aligned, and if the sink or cabinet is severely jarred, the joint may crack or break open, permitting water leakage therethrough.

Other prior art constructions have provided a rubber gasket between a sink and an adjacent cabinet top, normally held compressed by spaced bolts connected through the abutted sheet metal side walls of the adjacent cabinets therebelow. However, if the sink or cabinet in such a construction is severely jarred, the bolted cabinet side walls may spring, warp or flex in the intervals between bolts, or above and below the bolts, thereby separating the joint and the seal intended to be provided by the gasket, and permitting water to leak therethrough.

In other words, all prior art joint constructions are subject to failure by cracking open and leakage, because the cabinets, sinks and tops can be moved in relation to each other. Apparently there has been no satisfactory solution to this problem prior to the present invention.

Accordingly, it is a primary object of the present invention to provide a water-tight, crack-proof joint construction between a kitchen sink and an adjacent table or counter.

Furthermore, it is an object of the present

2

invention to provide a joint construction for kitchen sinks and cabinets in which the sink top, the adjoining cabinet, and its top are rigidly locked or tied together to prevent breaking the joint therebetween and thereby losing a desired and necessary water-proof characteristic.

Furthermore, it is an object of the present invention to provide a joint construction between a sink and an adjacent cabinet top in which the sink and adjacent cabinet top cannot be moved in relation to each other so that the joint cannot be pulled apart to result in cracks and leakage.

Also, it is an object of the present invention to provide a water-tight, crack-proof joint construction between a kitchen sink and the top of an adjacent cabinet in which the sink and top are aligned and held in alignment in forming the joint.

Moreover, it is an object of the present invention to provide a water-tight, crack-proof joint between a sink and the top of an adjacent cabinet, or between tops of adjacent cabinets, which may be readily formed in installing additional cabinet units to original sink or sink and cabinet installations.

Likewise, it is an object of the present invention, to provide a new, water-tight, crack-proof joint construction which may be readily and inexpensively formed in connection with standard types of vitreous enameled, sheet metal sinks and sheet metal kitchen base cabinets.

Finally, it is an object of the present invention to provide a new joint construction for a kitchen sink and an adjacent table or counter which avoids the prior art difficulties, satisfactorily solves the problem existing in the art, and incorporates the foregoing advantages in a simple and effective manner.

These and other objects and advantages appear to those skilled in the art from the following description and claims may be obtained, the stated results achieved, and the described difficulties overcome, by the devices, constructions, arrangements, combinations, sub-combinations, parts and elements which comprise the present invention, the nature of which is set forth in the following general statement, preferred embodiments of which—illustrative of the best mode in which the applicant has contemplated applying the principle—are set forth in the following description and shown in the drawings, and which are particularly and distinctly pointed out and set forth in the appended claims forming part hereof.

The nature of the improvements in water-tight, crack-proof joint construction may be stated in general terms as preferably including in combination with a sink having a depending flange terminating in an inturned flange and a sheet metal counter top extension for the sink

having a depending flange terminating in an inturned flange, of means for joining the sink and counter top including sealer strip means extending longitudinally of the joint and transverse to and substantially normal to the planes of said depending flanges, means connecting said strip means to said inturned flanges, trim means having a portion extending between said depending flanges and connected with said strip means, joint waterproofing means between the trim means and depending flanges, a sheet metal cabinet panel end wall having an inturned top flange, and means locating the sealer strip means with respect to said top flange.

By way of example, preferred embodiments of the improved joint construction are illustrated in the accompanying drawings forming part hereof wherein;

Figure 1 is a perspective view of a sink and cabinet unit, and an adjacent base cabinet unit, provided with the improved water-tight, crack-proof joint between sink and cabinet top;

Fig. 2 is a section taken as on the line 2—2, Fig. 1;

Fig. 3 is an expanded view similar to Fig. 2 of certain of the parts shown in Fig. 2 prior to assembly;

Fig. 4 is an expanded view similar to Figs. 2 and 3, showing some of the parts in the course of assembly;

Fig. 5 is an expanded perspective view of a portion of the base cabinet panel front, end and side walls and joint locking or sealer strip used in the joint illustrated in Figs. 1 to 4;

Fig. 6 is a view similar to Fig. 2 of a modified form of construction;

Fig. 7 is a side view of the trim member used in the construction shown in Fig. 6;

Fig. 8 is a view similar to Figs. 2 and 6 of another modified form of construction;

Fig. 9 is a sectional view taken on the line 9—9, Fig. 8;

Fig. 10 is a view similar to Figs. 2, 6, and 8, showing a still further modified form of construction;

Fig. 11 is a view similar to Fig. 2, illustrating an improved joint construction between adjacent base cabinets taken as on the line 11—11, Fig. 12; and

Fig. 12 is a perspective view similar to Fig. 1 of two adjacent base cabinets equipped with the improved joint construction.

Similar numerals refer to similar parts throughout the various figures of the drawings.

A sink and under sink cabinet unit is indicated generally at 1 in Fig. 1, and an adjacent base cabinet unit is indicated at 2. Referring to Figs. 2, 3 and 4, the sink unit 1 includes a vitreous enameled sink 3 which, as illustrated, may be formed of sheet metal with a vitreous enamel coating. The under sink cabinet for the sink unit 1 includes sheet metal walls, one vertical sink supporting side or end panel wall being indicated at 4 in Figs. 2, 3 and 4. The sink 3 is provided with a top having an integral rim 5 formed with an imperforate depending vertical side rim flange 6 which terminates in an inturned flange 7. The flange 7 is usually angled upward as shown. As shown in the drawings, the under-sink cabinet side panel wall extends below and substantially in the plane of the depending sink flange 6.

The kitchen base cabinet unit 2 has vertical table top supporting sheet metal panel walls 8 within which shelves or drawers may be mounted.

The front of cabinet 2 may be closed by a door or drawer ends. Drawers 9 are indicated in Fig. 1. The base cabinet panel side walls 8 preferably terminate in an inturned top flange 10. The top 11 of the base cabinet unit 2 forms a work table, counter or platform which may provide a continuous working surface adjacent the sink unit 1 when the base cabinet unit 2 is located adjacent the sink unit 1 as illustrated in Fig. 1.

5 The cabinet top 11 may be formed with a sheet metal top wall 12 having an imperforate depending vertical side flange 13 terminating in an inturned flange 14. The work surface of the top 11 may be formed of linoleum or plastic or rubber sheet material 15, or the like, glued, cemented or otherwise secured to the sheet metal top wall 12. A channel shape nosing and trim strip 16 sometimes formed of stainless steel may be provided embracing the sheet metal top wall 12, and flanges 13 and 14, and the member 16 binds the edge of the softer surface material 15. Adhesive cement 25 is spread between the trim member 16 and the walls 12, 13 and 14 and the covering 15 of the top member 11. Bolt holes 17 are formed in the cabinet top flange 10, and bolt holes 18 are formed in the top flange 14 and trim strip 16. The bolt holes 17 and 18 are aligned and the cabinet top 11 is normally secured to the cabinet panel walls 8 by bolts extending through said holes 17 and 18, with a panel side wall 8 extending below and substantially in the plane of a depending table top side flange 13, as shown in the drawings.

Thus far, the sink and cabinet units 1 and 2 described are of known construction. The prior practice has been to bolt the sink cabinet panel wall 4 to the base cabinet panel wall 8 when installing a base cabinet unit 2 adjacent sink unit 1; and to provide a gasket or adhesive cement between trim member 16 and sink flange 6 in order to form a water-proof joint. However, if the cabinet is jarred, the thin sheet metal panel walls 4 and 8 may spring, flex or warp, permitting the cabinet top 11 to move relative to the sink 3 and the joint therebetween to crack open. The present invention is particularly concerned with forming a water-tight, crack-proof joint between the cabinet top 11 and sink 3.

In accordance with the present invention, a 50 joint sealing and locking strip or bar 19 (Fig. 5) is provided, extending longitudinally of the joint and transverse to and substantially normal to the depending flanges 6 and 13. The strip 19 is formed with bolt holes 20 adapted to register with the bolt holes 17 and 18 in the panel top flange 10 and the cabinet top flange 14. The sealer strip 19 has a longitudinally extending angled portion 21, hooked over at 22, so as to embrace and grip the inner edge of sink flange 7 continuously throughout its length. Downwardly projecting pins 23 are secured to the locking strip 19 near either end thereof; and holes 24 are formed in the top flange 10 of the end panel 8 of the base cabinet. The location of the holes 24 55 matches the location of pins 23 so that when pins 23 are inserted in holes 24, the bolt holes 20 of locking strip 19 are aligned with bolt holes 17 in cabinet top flange 10.

In forming the improved joint, the cabinet top 11 is removed from the cabinet unit 2, as indicated in Fig. 3. The hooked portion 22 of locking strip 19 is hooked over sink flange 7 as indicated in Fig. 4; and the cabinet end panel 8 is moved over and located adjacent or against the end panel 4 of the cabinet of sink unit 1. Pins 23

are inserted in holes 24 to locate, align and lock the cabinet panel wall 8 with respect to the sink 3 and sink end panel 4 as shown in Fig. 4. Adhesive putty, mastic, cement, or caulking compound 25 is then smeared on the edge of the downturned sink rim flange 6 and the locking strip 19, as indicated in Fig. 4. The cabinet top 11 is then forced into place and bolts 26 are inserted through aligned bolt holes 17, 18 and 20 for securely and rigidly connecting the sink 3 through the locking strip 19 to the cabinet top 11, cabinet end panel 8 and cabinet trim 16 as shown in Fig. 2, the sink side flange 6 thus being located adjacent the table top side flange 13.

In bolting the joint, the adhesive cement 25 is squeezed tightly into all crevices between portions of the abutted sink flange 6, trim member 16 and locking strip 19, as indicated in Fig. 2; and surplus cement may be struck off at 27 to leave a slightly depressed joint between the sink 3 and cabinet top 11.

Since the sink 3 and cabinet top 11 are anchored rigidly along the entire length of the abutted portions thereof by the locking strip 19, they cannot be moved relative to one another. Thus, the joint between the sink unit 1 and base cabinet 2 cannot be pulled apart to cause the cement 25 to crack or to cause leakage of water along the joint or down between the panel walls 4 and 8.

The adjusting screw 28, indicated in Figs. 2, 3 and 4, is for leveling the sink when initially installing the sink, or for separating the sink 3 and sink panel 4 in order to lock the sealing strip 19 to the sink flange 7.

In the alternate form of construction shown in Figs. 6 and 7, the trim member 16a may be formed as an extruded metal section to have a generally T-shaped flange means or portion 29 at the top of its vertical web portion so as to overlap both the sink 3 and the linoleum facing 15 of the cabinet top 11 and to cover the joint therebetween. Thus, the head 29 of the trim member 16a binds the edge of the linoleum facing 15 and also confines the adhesive cement 25 so as to eliminate any exposed cement material which is present at 27 in the joint illustrated in Fig. 2.

The longitudinally extending bottom flange 30 of the trim member 16a is provided with holes 31 which are aligned with holes 18 in the cabinet top 11. The joint illustrated in Fig. 6 is assembled in the same manner as described in connection with the joint illustrated in Fig. 2 with the web of the trim member 16a located between the adjacent side flanges 6 and 13, respectively, of the sink and table top and extending longitudinally of the joint, and with the flange 30 located between the table top flange 14 and base cabinet top flange 10. The trim member 16a and its T-shaped flange means 29, as shown in Fig. 7, may be shaped at its front end 32 to conform to the front edge of the cabinet top 11, and may be shaped at its rear end 33 to conform in longitudinal contour to the cove and shallow upstanding splash back at the rear of the cabinet top 11 and sink 3. As shown in the drawings, the cove and splash back at the rear of the cabinet top 11 and sink 3 present at the tops of their respective adjacent depending side flanges 13 and 6, a matching contour lying in a plurality of planes at right angles to said side flanges 13 and 6.

In the modified form of construction shown in Figs. 8 and 9, the locking strip and trim member are combined in one piece as an extruded section generally indicated in Fig. 8 at 19a. The member 19a includes a T-shaped flange means or

portion 29a at the top of its vertical web portion 34 which laps the sink 3 and binds the linoleum 15 of the cabinet top 11 and covers the joint therebetween. A central web 34 extends downward longitudinally of the joint between the sink flange 6 and cabinet top flange 13. The bottom of member 19a is shaped generally to conform to the construction of the locking strip 19 and has a longitudinally extending flange portion 35 located between the table top flange 14 and base cabinet top flange 10 and provided with bolt holes 36 matching the bolt holes 17 and 18. The other flange at the bottom of member 19a has a portion 21a hooked at 22a to grip the sink flange 7. Pins 23a are provided in portion 35 which function in assembling the joint (Fig. 9) in the same manner as the pins 23 of the locking strip 19.

As stated, the member 19a combines the function of the locking strip and trim and binding members in one piece for joining and locking a sink top to a cabinet top. Sealing compound 25 is applied to the various surfaces to be joined before assembly, and the joint shown in Fig. 8 is assembled in the same manner as described in connection with the joint illustrated in Fig. 2.

In the modified form of construction shown in Fig. 10, a combined locking strip and trim member 19b, similar to the member 19a of Fig. 8, is used without requiring an extruded section. The trim member 19b includes two steel channel members of modified form 37 and 38, welded at 39 back to back, with a stainless steel trim strip 40 enclosing the top of the T formed by the top flanges of the channels 37 and 38. The back to back welded channel members form a vertical web located between the adjacent side flanges 6 and 13, respectively, of the sink and table top and extends longitudinally of the joint formed therebetween. The channel member 37 has a lower flange 41 similar in construction and function to the left-hand portion of locking strip 19; and the channel member 38 has a lower flange shaped with an angled portion 21b and a hook portion 22b similar in construction and function to the portions 21 and 22 of the locking strip 19. The joint illustrated in Fig. 10 is assembled in the same manner as the joint of Fig. 8.

A joint, in accordance with the present invention, is illustrated in Fig. 11 between two adjacent base cabinet units 2 as shown in Fig. 12. In the joint of Fig. 11, a combined locking strip and trim member 16b is formed as an extruded section having bottom flanges 30a in both directions similar to the bottom flange 30 of the member 16a. The member 16b is assembled with the cabinet panel walls 8 and the cabinet tops 11 in the same manner as described in connection with the assembly of the joints illustrated in Figs. 2, 6, 8 and 10. Locating pins (not shown) similar to the pins 23 or 23a are provided on one or both of the flanges 30a to accurately locate and align the various members for being bolted in assembled relationship. If desired, the member 16b, instead of being an extruded section as illustrated, may be formed of steel channel members and a stainless steel trim member in the same manner that the member 19b of Fig. 10 is formed.

Accordingly, in each of the embodiments of the present invention illustrated, there is a trim member and a locking and sealing strip formed of one or two or more pieces connected together and extending longitudinally of the joint, with the locking strip portion thereof extending transverse to and substantially normal to the planes of the depending flanges of the sink and cabinet

tops joined thereby. There is also means connecting a portion of the sealing strip to the in-turned flange of the cabinet top. There is also means connecting another portion of the locking strip to the sink or to another cabinet top. Finally, there is means for locating and aligning the locking strip with respect to the parts to be joined so that when the joint is finally formed, it is properly aligned and securely locked and anchored.

Accordingly, the present improvements provide a joint which may be readily formed between a kitchen sink and the top of an adjacent cabinet which may form a table or counter extension for the sink, or between the tops of adjacent cabinets, which joint is securely held and anchored throughout its length so that the members joined cannot move relative to one another, thus providing a crack-proof and water-tight joint construction which avoids the described difficulties heretofore present in prior art constructions.

Finally, in the foregoing description, certain terms have been used for brevity, clearness and understanding; but no unnecessary limitations are to be implied therefrom beyond the requirements of the prior art, because such words are utilized for descriptive purposes herein and not for the purpose of limitation, and are intended to be broadly construed. Moreover, the embodiments of the improved joints illustrated and described are by way of example and the scope of the present invention is not limited to the exact details of construction of the various parts.

Having now described the features of the invention, the manufacture and assembly of preferred embodiments of the improved joint construction, and the advantageous, new and useful results attained thereby; the new and useful devices, constructions, arrangements, combinations, sub-combinations, parts and elements, and reasonable mechanical equivalents thereof, obvious to those skilled in the art, are set forth in the appended claims.

I claim:

1. In combination, a vitreous enamel coated sheet metal sink having a top and an imperforate depending vertical side rim flange terminating in an in-turned flange, an undersink cabinet having a vertical sink supporting sheet metal panel side wall extending below and substantially in the plane of said depending sink side flange, a table top including an upper sheet metal wall having an upper surface facing of softer material, said upper table top wall being formed with a depending vertical side flange terminating in an in-turned flange, a base cabinet having a vertical table top supporting sheet metal panel side wall extending below and substantially in the plane of said depending table top side flange terminating in an in-turned top flange, said undersink and base cabinet side walls being located adjacent each other, said depending sink and table top side flanges being located adjacent each other; the rear of the sink and table tops each being formed with a cove and an upstanding splash back presenting at the tops of their adjacent depending side flanges a matching contour lying in a plurality of planes at right angles to said adjacent side flanges; combined metal sink and table top joint trim and locking strip means; said strip means including a vertical web portion located between said adjacent side flanges and extending longitudinally of the joint formed therebetween;

5 a longitudinally extending flange at the bottom of the web portion located between the table top inturned flange and the base cabinet inturned top flange; means connecting the sink, table top, undersink cabinet, base cabinet and strip means together in rigid anchored joint forming relation; and T-flange means at the top of the strip means web portion shaped to conform in longitudinal contour to said matching sink and table top contour and covering the joint between the sink and table top along said matching contour.

2. In combination, a vitreous enamel coated sheet metal sink having a top and an imperforate depending vertical side rim flange terminating in an in-turned flange, an undersink cabinet having a vertical sink supporting sheet metal panel side wall extending below and substantially in the plane of said depending sink side flange, a table top including an upper sheet metal wall having an upper surface facing of softer material, said upper table top wall being formed with a depending vertical side flange terminating in an in-turned flange, a base cabinet having a vertical table top supporting sheet metal panel side wall extending below and substantially in the plane of said depending table top side flange terminating in an in-turned top flange, said undersink and base cabinet side walls being located adjacent each other, said depending sink and table top side flanges being located adjacent each other; the rear of the sink and table top each being formed with a cove and an upstanding splash back presenting at the tops of their adjacent depending side flanges a matching contour lying in a plurality of planes at right angles to said adjacent side flanges; combined sheet metal sink and table top joint trim and locking strip means; said strip means comprising two channel members welded back to back and a trim strip; said back to back welded channel members forming a vertical web located between said adjacent side flanges and extending longitudinally of the joint formed therebetween; one of the lower channel flanges at the bottom of the web extending longitudinally of and being located between the table top in-turned flange and the base cabinet inturned top flange; the channel top flanges forming T-flange means at the top of the web; said trim strip enclosing the top of the T-flange means; said T-flange means being shaped to conform in longitudinal contour to said matching sink and table top contour and covering the joint between the sink and table top along said matching contour; and means connecting the sink, table top, undersink cabinet, base cabinet and strip means together in rigid anchored joint forming relation.
